UNITED STATES PATENT OFFICE

FRANK J. ABEL, OF MASSEPEQUA, NEW YORK, ASSIGNOR TO HENRY HYMAN, OF BROOKLYN, NEW YORK

DESIGN FOR A LAMP BASE

Application filed December 2, 1932. Serial No. 46,280. Term of patent 7 years.

To all whom it may concern:

Be it known that I, FRANK J. ABEL, a citizen of Germany, residing at Massapequa, county of Nassau, and State of New York, have invented a new, original, and ornamental Design for a Lamp Base, of which the following is a specification, reference being had to the accompanying drawing, forming a part thereof, in which Fig. 1 is a perspective view

of one side of the device, a portion of the lamp support being broken away for convenience of illustration, and Fig. 2 is a perspective view at right angles to Fig. 1 showing my new design.

I claim:

The ornamental design for a lamp base, as shown.

FRANK J. ABEL.
